INGOT FOR TYPESETTING MACHINE
FEEDERS

Albert H. Jung, New York, N. Y., assignor to
United American Metals Corporation, Brooklyn, N. Y., a corporation of New York

Application December 10, 1936, Serial No. 115,077

3 Claims. (Cl. 22—218)

This invention relates to type metal ingots and particularly to the kind that are fed gradually into the pot of a type setting and casting machine.

5 It has been customary in the past to hang an ingot of type metal on the hook of a feeding machine in such a manner that the ingot dips into the pot of molten metal provided in type casting and setting machines such as are known, for example, as "Linotype" and "Monotype" machines. As the metal in the pot is consumed for the casting of type, the feeding machine lowers the ingot further into the pot. Ingots of this character are frequently called "Maigach" 10 ingots.

Difficulty has been experienced in the past, however, in the handling of such ingots because they weigh about twenty pounds or more each and must be reduced in thickness at one end at least and perforated for the reception of a hook. 20 In shipping such ingots or carrying them about or hanging them on the hooks of feeding machines, they are likely to break off at the end where they are perforated. The perforated end has been made comparatively thin to permit the rather heavy ingot to be readily hung on the hook. The consequent weakness of said ends causes them to break and thereby to necessitate either the formation of a new hanging hole therein or the re-melting of the ingot and the re-molding thereof. When the ends of the ingots are made of sufficient thickness to resist breakage thereof, the perforation therein for the reception of the hook nevertheless makes it difficult to hang the ingot on the hook in the exact vertical position in which it should hang for proper feeding into the melting pot. Furthermore, the end part of the ingot nearest the hook is retained on the hook and must be lifted off 30 the hook manually and dropped into the pot. Otherwise the feeding machine will carry the hook down into the molten metal and unduly heat the hook as well as coating it with the type metal, so that the heated hook and the necessity for 35 peeling off the attached metal therefrom for the reception of the next ingot, retards the operation.

My invention therefore contemplates the provision of an ingot which can be readily hung on the hook of the feeding machine regardless of 50 which end is uppermost and which when hung on the hook hangs perfectly straight in the proper position for feeding into the pot, because the hook fits into an accurately centered curve.

My invention further contemplates the provision of an ingot having end ears of sufficient

strength to prevent said ears from breaking off during the handling of the ingot and hanging it on the hook.

My invention further contemplates the provision of an ingot, the end part of which will automatically fall into the pot without the necessity for any attention on the part of an operator or supervisor or other mechanic.

The various objects of my invention will be clear from the description which follows and from the drawing, in which,

Fig. 1 is a front view of my new ingot as it appears in its feeding position, the hook of the feeding machine and the pot of the type-casting machine being shown in dash-dot lines.

Fig. 2 is a side view of the same.

Fig. 3 is a perspective view of one of the ends of the ingot.

In the practical embodiment of my invention which I have shown by way of example, the main body portion 10 of the ingot is made of the usual shape having converging sides 11 and 12 and an upper surface 13 somewhat narrower than the lower surface 14 thereof.

In order that either end of the ingot may be hung upon the hook, both ends are made identical in shape. Said ends, however, are made of sufficient thickness of material to prevent breakage thereof while nevertheless permitting the ingot to be swung over the hook 15 of the feeding machine. For this purpose I provide the upper bevelling surface 16 which extends from the extremity of the top surface 13 to the adjacent end of the ingot. Said surface 16 is concave upwardly and reduces the thickness of the end portion of the ingot to about half the thickness of the body portion 10 thereof. Intermediate the sides 11 and 12 I provide the substantially V-shaped slot or opening 17 dividing the end portion of the ingot into two similar ears 18 and 19. The slot 17 is reduced in width toward the inner end thereof as at 20 and said slot is made of substantial length, that is, the length of the slot is about twice the thickness of the ingot at its body portion. The inner walls of the ears 18 and 19 which form opposed walls of the slot, taper downwardly and inwardly toward each other from the outer surfaces of said end parts to provide a bevelled edge portion 21 at the bottom of the slot. Projecting into the slot at the ends of each of the ears 18 and 19 are the hook-engaging lugs 22 and 23. Said lugs extend toward each other partway across the slot 17 but not far enough to close said slot.

The height of each of said lugs may be slightly greater than half the thickness of the extreme end portion of the ears. The inner walls of said lugs, however, are bevelled upwardly and outwardly and are continuous with the inner walls of the ears 18 and 19, whereby said lugs provide bevelled edges continuous with the bevelled edge 21 of the slot for engagement by the hook 15. The inner edges 24 and 25 of said lugs diverge 10 from the middle part of said lugs in a direction away from the adjacent end and thereby form cam surfaces thereon which automatically adjust themselves on the hook 15 under the weight of the ingot to hold the ingot in exact vertical 15 position on the hook.

Since both ends of the ingot are made identical, a description of the other end is deemed unnecessary. By making both ends of the ingot alike, it will be seen that the ingot may be lifted 20 with either end uppermost as may be found convenient and swung over the hook so that the hook enters the slot 17 whereafter the ingot may be released. The hook engages the bevelled and tapered edges 24 and 25 and by reason of its 25 cam action therewith, should the ingot not be originally hung straight on the hook, the ingot nevertheless swings into its proper vertical position. The hook engages only a comparatively small portion of the ingot because of the provision of the lugs 22 and 23 and of the peculiar 30 shape of said lugs. Danger of arranging the ingot improperly on the hook 10 is thereby substantially minimized. As the ingot is fed into the pot 26 and as the hook approaches said pot, no 35 attention need be paid thereto when the bottom end of the slot 17 has entered the pot. However, there remains nothing to hold the ears 18 and 19 together and because of the inclination of the edges 24 and 25, the ears 18 and 19 will fall away 40 from the hook, and into the pot automatically. The operator or machinist, therefore, need merely hang a new ingot on the hook in the proper position to enter the pot. Because of the provision of the lugs 22 and 23 which lugs only 45 engage the hook, it becomes unnecessary to reduce the thickness of the ends to the thickness of said lugs, but the thickness of said ends may be made substantially greater than that of the lugs 50 and the ears 18 and 19 are thereby sufficiently

strong to resist breakage under the conditions of practical use.

It will be seen that I have provided an ingot which can be readily handled, which hangs automatically in its proper position on the hook of a feeding machine and the end part of which automatically becomes separated into two parts which drop into the pot at the proper time. It will further be seen that I have provided an ingot having new characteristics well designed to meet the requirements of practical use.

While I have shown and described certain specific embodiments of my invention, I do not wish to be understood as limiting myself thereto, but desire to claim my invention as broadly as may be permitted by the state of the prior art and the scope of the appended claims.

I claim:

1. An elongated ingot having a bifurcated end portion providing a pair of transversely spaced elongated arms adapted to receive a hook therebetween, and hook-engaging lugs integral with and projecting inwardly from the arms, each of said lugs being shorter, narrower and thinner than the arm from which it projects.

2. In an ingot having a bottom face and a narrower top face, a bifurcated end portion providing a pair of elongated arms spaced transversely apart a distance sufficient to receive a hook therebetween, and a lug extending inwardly from each arm and terminating outwardly of the center line of the ingot and partly obstructing the space between said arms, said lug being shorter, narrower and thinner than the arm from which it extends and being provided with bevelled hook-engaging surfaces, the extensions of which form a V.

3. In an ingot, a body portion, a bifurcated portion at an end of the ingot providing a pair of elongated arms spaced apart transversely, each of said arms extending longitudinally from the body portion and being of increasing cross-sectional area throughout the length thereof, the cross-sectional area of said arms being greatest where the arms join the body portion, and a lug extending inwardly from the end portion of each of the arms, said lug being shorter, narrower and thinner than the arm from which it extends.

ALBERT H. JUNG. 50
